OUTBOARD MOTOR

Vern O. Lovegreen, St. Paul, Minn., assignor to Sports Jet, Inc., Minneapolis, Minn., a corporation of Minnesota

Filed June 9, 1969, Ser. No. 17,570

Term of patent 14 years

Int. Cl. D12—14

U.S. Cl. D71—1

Fig. 1.

Fig. 5.

Fig. 4.

Fig. 3.

Fig. 2.

FIG. 1 is a side elevation view of an outboard motor showing my new design;

FIG. 2 is a rear elevational view thereof;

FIG. 3 is a front elevational view thereof with the control handle in an alternative position;

FIG. 4 is a top plan view thereof; and

FIG. 5 is a bottom plan view thereof.

The opposite side of the outboard motor is essentially a mirror image of FIG. 1.

I claim:

The ornamental design for an outboard motor, as shown and described.
